UNITED STATES PATENT OFFICE

ROSS DAVID SIRAGUSA, OF CHICAGO, ILLINOIS

POWER PACK

Application filed January 23, 1929. Serial No. 334,543.

This invention relates to a power pack and particularly to one wherein a transformer may be completely assembled in a casing ready for installation in electrical circuit 5 and one which is especially useful in radio sets.

The invention contemplates also provision for mounting a fuse in the casing in such manner as to be protected against damage 10 and which at the same time allows ready removal and replacement of the fuse.

An object of the invention is to provide a power pack casing with a recess for the reception of a fuse.

15 Another object of the invention is to provide a unitary encased transformer assembly which may be attached to a support and connected in circuit outwardly of the case.

A further object of the invention is to 20 provide an incased transformer pack having a fuse arranged inwardly of the casing in such manner that the fuse may be readily removed and replaced.

The above, other and further objects of 25 the invention will be apparent from the following description, accompanying drawings and appended claims.

According to the invention a metallic casing having a depression in one side for a 30 fuse is arranged to receive a transformer and when the transformer has been inserted and electrical connections made with lugs extending through the bottom of the casing, the interior of the same is filled with plastic 35 insulating material and a cover placed over the casing so that the same is completely incased in metal. Attaching screws or bolts are fastened in the bottom of the casing and extend outwardly whereby the pack may be 40 readily mounted on a shelf or other support.

The form chosen to exemplify the invention is illustrated in the accompanying drawings and the views thereof are as follows:

45 Figure 1 is a front elevational view of a transformer embodying the invention.

Figure 2 is a top plan view of the casing employed in the arrangement of Figure 1.

50 Figure 3 is an enlarged fragmental partial sectional view showing details of construction.

Figure 4 is an enlarged transverse vertical sectional view through the pack.

Figure 5 is a fragmental sectional view showing the fuse recess.

The invention is directed to an A. C. power 55 transformer familiarly known in the radio art as a power pack. The transformers are mounted in metal containers and embedded in sealing compounds and usually are not provided with fuses or other protective devices. 60 It is usual practice when applying a power pack to a radio set to provide a fuse outwardly of the pack for protecting the transformer. This invention is directed to the arrangement 65 of a fuse in the power pack itself with the fuse in the primary transformer circuit and so arranged inwardly of the outer surface of the casing so that the pack may be assembled and shipped without danger of damage to the 70 fuse.

The form of casing illustrated in the accompanying drawings includes a rectangular wall 1 of metal which has a cut-out 2 in the bottom side thereof which cut-out is substantially coextensive with the bottom. A back 75 3 of metal having a flange 4 thereabout is secured to the ring 1 in any suitable manner, such as by welding or the like.

The top has a small cut-out 5 in which is sunk a metallic pocket 6 which pocket is secured in position by the flanges 7 thereof being outturned and welded or otherwise fastened to the wall 1. The bottom of the pocket member 6 is provided with two spaced openings 8 and 9.

80 The marginal portion of the bottom of the wall 1 is provided with a plurality of openings 10 and bolts or screws 11 are disposed in these openings to extend outwardly of the bottom. The screws are welded or otherwise 85 secured in the openings 10 so as to be immovable with respect to the same.

90 A fuse support 11 of insulating material corresponding to the shape of the pocket or cup 6 is inserted in the pocket supplied with two spaced fuse clips 12 and 13. The clips are secured in the insulating block 11 by fingers 14 crimped against the underside of the block. Each of the clips 12 and 13 has a conductor 15 passing through the block 11 and 100

extending into the openings 8 and 9 of the pocket or cup 6 so that electrical connection may be made with these conductors when the transformer is assembled in the casing.

A bottom insulating block 16 is disposed in the bottom of the casing and is supported on the uncut portion of the bottom of the wall 1. The block 16 has recesses 17 formed in the same so as to surround the heads of the screws or bolts 11 to enable the block 16 to rest firmly on the bottom of the wall 1.

A plurality of connecting lugs 18 are fastened at spaced intervals in the block 16. The lugs are formed from flat strips and then crimped in the metal against the top and bottom surface of the block 16 after the lugs have been passed through slits in the block. This arrangement positions the lugs 18 in vertical position so that connections may be made with various leads from the secondary of the transformer inwardly of the casing and to enable external connections to these lugs outwardly of the casing.

The lugs are provided with marginal slots 20 and holes 21 so that the electrical conductors may be joined either in the slots or in the holes as desired.

The fingers or lugs 15 of the fuse clips 12 and 13 may be of the same character as the lugs 18.

The fingers or lugs 15 of the fuse clips 12 and 13 are connected in the primary circuit of the transformer. The various terminals from the secondary winding of the transformer are connected to the several lugs 18 extending through the bottom of the pack.

A cover 22 similar in all respects to the back wall 3 is applied over the open space of the transformer casing after the transformer has been installed and electrically connected and the sealing compound applied.

The structure resulting from a pack constructed in accordance with this invention is compact, may be readily assembled on a support by passing the screws 11 through suitable openings in the support and applying nuts to the screws and then connecting conductors to such of the lugs 18 as the particular wiring arrangement demands. The provision of the fuse in the primary circuit of the transformer eliminates shorts in the transformer thus preventing burning out of the winding and also prevents melting of the sealing compound.

The arrangement of the fuse A in the pocket or cup allows the fuse to be installed in the pack at the time of manufacture so that the pack may be readily shipped and assembled without any damage resulting to the fuse.

The fuse A is of any standard type suitable for connection with the spring clips 12 and 13.

The transformer windings have not been shown in the drawings as these windings are

of standard arrangement consistent with the service the transformer is to render.

Certain of the lugs 18 are employed for supplying current to the primary winding of the transformer within the pack.

The fuse pocket or cup 6 may be arranged on any convenient portion of the pack and is not to be limited to arrangement on the top of the same as shown in the drawings as of course any other disposition of this may be made to suit the conditions of manufacture.

The fuse pocket or cup enables mounting of the fuse in a sunken recess within the plane of the case.

The fuse recess may be covered by a name plate or other suitable cover pivoted or otherwise arranged over the same.

It will be observed that a pack constructed in accordance with this invention is compact, self contained and arranged to be readily mounted in connection with electric circuits. The provision of a fuse in a recess enables the transformer to be properly provided with suitable fuse at the time of manufacture which fuse is protected against damage in transit or use.

The fuse block 11 may be removably arranged within the pocket 6 instead of being fastened by the clips 14 as hereinabove mentioned. Spring fingers 23 may be formed in the cup or pocket 6 to prevent displacement of the block 11 and its supported fuse A. In such construction the clips 14 would not be used.

The invention has been described herein more or less precisely, yet it is to be understood that changes may be made in the arrangement and proportion of parts and that equivalents may be substituted without departing from the spirit and scope of the invention.

The invention is claimed as follows:

1. In an arrangement for housing the transformer of an eliminator and the fuse thereof, a sheet metal rectangular box having an opening in one of its sides, a flanged sheet metal tray mounted on the side and registering in the opening and having its bottom inwardly of the plane of the side, an insulating block within the tray, and spring clips mounted on the said block arranged to removably secure a fuse inwardly of the plane of the side of the box.

2. In an arrangement for housing the transformer of an eliminator and the fuse and terminals thereof, a sheet metal rectangular box having an opening in one of its sides, a flanged sheet metal tray mounted on the side and registering with the opening and having its bottom inwardly of the plane of the side, means in the tray arranged to removably secure a fuse inwardly of the plane of the side, another side of the box having an opening therein, an insulating block

mounted on the last named side within the box and registering with opening, the said insulating block having a slit formed therein, and a terminal positioned in the slit of the insulating block, the said terminal comprising a strip of conducting material having an intermediate portion doubly bent and pressed against the block whereby end portions extend normally on either side of the block.

3. In an arrangement for housing the transformer of an eliminator and the fuse therefor, a sheet metal rectangular box having an opening in one of its sides, a flanged sheet metal tray mounted on the side and registering in the opening and having its bottom inwardly of the plane of the side, means arranged to secure the tray in position, the said means including a resilient tongue formed in a side wall of the tray arranged to abut the under surface of the side of the box, and means in the tray arranged to removably secure a fuse inwardly of the plane of the side of the box.

In testimony whereof I have hereunto subscribed my name at Chicago, Cook County, Illinois.

ROSS DAVID SIRAGUSA.
